UNITED STATES PATENT OFFICE.

JOHN S. NICHOLL, OF CAMBRIDGE, MASSACHUSETTS, ASSIGNOR TO ELECTRIC BOILER CORPORATION, OF CAMBRIDGE, MASSACHUSETTS, A CORPORATION OF MASSACHUSETTS.

COMBINED LAVATORY AND WATER-HEATER.

1,378,185.

Specification of Letters Patent. Patented May 17, 1921.

Application filed January 29, 1921. Serial No. 440,967.

To all whom it may concern:

Be it known that I, JOHN S. NICHOLL, a citizen of the United States, residing at Cambridge, in the county of Middlesex and State of Massachusetts, have invented new and useful Improvements in Combined Lavatories and Water-Heaters, of which the following is a specification.

The present invention relates to lavatories, and more particularly to a means for combining therewith a heating device adapted to supply water at a desired temperature to the lavatory.

An object of this invention is to provide a lavatory structure embodying as a part thereof a heater for supplying heated water at the desired temperature to the lavatory and also for maintaining the basin of the lavatory at a predetermined heated temperature.

The invention further aims at the provision of a lavatory arranged with a heater and pipe lines for taking off cold water in the usual manner and for also taking a desired quantity of the cold water, heating it and delivering the heated water to a hot water outlet of the lavatory.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a top plan view of a lavatory constructed according to the present invention and combining therein the heating and piping features;

Fig. 2 is a front elevation of the same;

Fig. 3 is a side elevation thereof, showing the draining connections;

Fig. 4 is a front elevation of the device, partly in section and disclosing the construction of the water heater embodied in the pedestal and base of the lavatory;

Fig. 5 is a side elevation similar to Fig. 3, showing the pedestal and base in section, and showing the complete drain pipe connections; and

Fig. 6 is a transverse section taken through the pedestal of the lavatory substantially on the line 6-6 of Fig. 2.

Referring to the drawings, 10 designates the basin of a lavatory supported upon a

pedestal 11 enlarged at its lower end to form a supporting base 12. The pedestal with its base and the basin 10 are preferably constructed of vitreous ware or enameled cast iron or other suitable material as is common in the art, and the pedestal is modified sufficiently to constitute an outer casing or shell for the heater which is subsequently to be described.

Within the pedestal 11 is placed an inner container 13 of considerably less diameter than that of the pedestal and being spaced concentrically therefrom to provide an inclosing jacket or space for the inner receptacle. The space or jacket is filled with a suitable heat-insulating material 14 which may be wool fiber or the like packed to the desired density in the space for maintaining to a large degree the heat of the water within the container 13.

A rheostat or heating element 15 is supported in one side of the container 13 and projects outwardly through the jacket 14 within an insulating block 16 of wood or the like which is interposed in the jacket 14. A cover plate 17 is fitted over the outer end of the opening for the rheostat to inclose the same and to permit easy access thereto when desired.

The container 13 is also provided with a thermostat 18 supported in the side of the container 13 and extending outwardly through the block 16 and provided with a gage or other visual indicator 19 which is supported exteriorly of the pedestal 11. The rheostat 15 is connected in any suitable manner to a source of electric energy for energizing the rheostat to heat water which is conveyed to the container 13.

The pedestal 11 is provided with a base plate 20 suitably secured to the bottom of the pedestal and which is adapted to support an insulating bottom 21 for the container 13, which bottom 21 projects upwardly into the container 13 to provide a heat non-conducting wall at the lower end of the pedestal and container.

This combined lavatory and water heater may be used where there is but one water supply pipe 22. The present illustration shows one arrangement of installation and wherein the pipe 22 rises at one side of and toward the rear of the lavatory, and has a branch pipe 23 leading to a cold water outlet faucet 24 which is mounted on the basin 110

10 of the lavatory. A hand controlled valve 25 is interposed between the pipe 22 and its branch 23 for cutting off the flow of cold water to the latter when desired.

5 The pipe 22 is provided, near the base 12 of the lavatory, with a second branch pipe 26 which leads directly into the lower end 10 of the container 13 at a point preferably below that of the rheostat 15. A hand valve 27 is mounted in the branch pipe 26 for closing off the supply of the water to the container 13 when desired, and the pipe 26 is also provided with a drain pipe 28 located between the valve 27 and the tank 13 and 15 which is controlled by a drain valve 29 permitting the draining of the tank 13 when desired.

The container 13 is connected at its upper end to a hot water supply pipe 30 which is 20 preferably led across the upper end of the pedestal 11 to the rear thereof and connected with a hot water outlet faucet 31 mounted on the basin 10 and also provided with a hand operated valve 32 for closing 25 off flow of hot water from the container 13 to the faucet 31.

While any suitable arrangement of the drain pipes for the tank and a basin may be had, in the present illustration the basin 30 10 is provided with a drain pipe 33 having the usual trap therein and which extends downwardly and is connected to the drain pipe 28 leading from the lower end of the tank 13. The connection between the pipe 35 33 and pipe 28 is below the valve 29 so that the basin 10 may be drained independently of the draining of the tank 13.

It will be apparent that the installation and structure of the combined lavatory and 40 water heater as above set forth requires connection to but one water supply pipe and that the structure of the pedestal embodying therein the water heater maintains the pedestal and the basin supported thereon at 45 a warm temperature at all times and supplies cold water and also hot water at the desired temperature to the basin.

It is obvious that various changes and

modifications may be made in the details of construction and design of the above specifically described embodiment of this invention without departing from the spirit thereof, such changes and modifications being restricted only by the scope of the following claims.

What is claimed is:—

1. In a combined lavatory and water heater, a pedestal, a container arranged within the pedestal, heating means in the pedestal for the container, a single water supply pipe connected to the bottom of the container, an outlet pipe connected to the top of the container and leading to the basin, a branch pipe leading from said supply pipe to the basin for admitting cold water thereto, and draining means connected to the container.

2. In a combined lavatory and water heater, a pedestal, a basin mounted on the pedestal, a container arranged within the pedestal, a single source of water supply, a branch connected to said source of water supply for supplying cold water to the basin, a second branch from said source of water supply connected to the lower end of the container for delivering cold water thereto, a heater in the pedestal for heating the water in the container, an outlet pipe connected to the top of the container and leading to the basin to supply warm water thereto, and valves in said branch pipes for permitting manual control of water through the branches.

3. In a combined lavatory and water heater, a pedestal having an outer shell, a basin supported on said shell, a container arranged within the shell, a heat non-conducting packing between the container and shell, means for conducting water to the lower end of the container, an outlet pipe connected to the upper end of the container and leading to the basin, and heating means mounted in one side of the pedestal and projecting into the container for raising the temperature of the water therein.

JOHN S. NICHOLL.
